METHOD AND APPARATUS FOR CONVERT-
ING HYDROCARBONS

John C. Black, Los Angeles, Calif., assignor, by
mesne assignments, to Gasoline Products Com-
pany, Inc., Wilmington, Del., a corporation of
Delaware

Application November 6, 1922, Serial No. 599,403

10 Claims. (Cl. 196—110)

This invention relates to the art of producing low boiling point hydrocarbons from those of high boiling point hydrocarbons and more particularly by the process described in my Patent 5 No. 1,426,813 in which the hydrocarbons are heated in a coil and maintained while being heated at a pressure sufficient to prevent vaporization of the hydrocarbons, and this application for Letters Patent refers particularly to 10 the method of operating and constructing the heating coil in the before mentioned Patent No. 1,426,813.

In the before mentioned patent I describe a process wherein I employ temperatures as high 15 as 1000° F. and pressures as high as 1000 pounds or more per square inch. To withstand these excessive temperatures and pressures, it is essential to construct the heating elements or coils in a very substantial and safe manner, and furthermore, it is advantageous to so construct the 20 coil that each pipe or tube can be easily opened for inspection and cleaning without dismantling it. It is also advantageous to be able to construct the coils outside of the furnace and insert them in the furnace as a complete coil only 25 requiring connection to the balance of the apparatus to make it operative.

I have discovered that the presence of sulphur in the hydrocarbons, either as free sulphur 30 or as sulphur compounds, will readily attack the steel of the tubes when the coil is in operation under the high pressure and high heat employed in the process. To overcome this difficulty, I prefer to use an alloy steel such as nickel 35 steel or chrome nickel steel, or I may use a tube which has been heat-treated with aluminum wherein a thin coating of aluminum iron or aluminum steel alloy is produced which acts as a protective surface to the tube and prevents to 40 a great extent the destructive action of the sulphur or sulphur compounds.

To withstand the high pressure employed in 45 the process and especially so under the high heat employed, I prefer to use a seamless drawn tube in preference to a pipe made by welding, such as the ordinary butt or lap-welded pipe of commerce, as I have found that such pipe will not stand the strains as well as the seamless tubing. However, I do not wish to limit myself in the construction of my coils, as either seamless or welded 50 seam pipe may be employed.

Referring to the drawing:

Figure 1 is a sectional elevation of the coil placed in the furnace.

55 Figure 2 is a plan view of the coil.

Figure 3 is an end elevation on the line 3—3 of Figure 2.

Figure 4 is a sectional view of the return connectors and clean-out blocks.

Fig. 5 is a sectional view of the coil clamps. 5

Like numbers refer to like parts in the various figures.

The furnace 1 is of brick construction and may have one or more compartments. In the drawing, 1 is shown as a furnace with three compartments, one for combustion space, one for the main coil 2 and one for the economizer coil 3. The furnace is fitted with a stack 4 to carry off the products of combustion; 5 is an oil or gas burner of the ordinary type; 6 is a door to afford access to the coil 2; 7 are the blocks which form the crossovers from tube to tube and 8 are clamps to hold the coil together; 9 are angle blocks for making connections one part with the other; 10 are plugs in the angle blocks and 10 coil blocks to afford means for inspection and cleaning the tubes; 11 is a connecting tube from the outlet of the coil to the digester or carbon catcher described in my Patent No. 1,426,813; 12 are the tubes shown in Figures 2 and 4; 13 the 15 threaded connection of the tube and block; 14, 15 and 16 are the three sections that go to make 20 up the clamp 8 shown in Figure 3. These three 25 sections are shown in cross section in Figure 5, the clamped tubes 12 being indicated in dotted 30 lines.

It will be noted in Figure 1 that the coil 2 is located entirely within the heating zone of the furnace with only the ingress and egress connections out of the heating zone—this I have 35 found desirable and in some cases necessary to prevent the corrosive action of the sulphur or sulphur compounds in the hydrocarbons being cracked, as I have found by experience that there is a thin coating of carbon deposited upon the 40 inside of the tubes which acts as a protective coating thereon and the sulphur present in the hydrocarbons will not attack the steel either in the tubes or the return connectors. This protective carbon or carbonaceous deposit is only 45 formed in the tubes or return connectors when they are inside the heating zone of the furnace and is due, I believe, to the baking action of the high heat found in the heating zone and to which the coil is subjected. This is a very important 50 feature of my cracking coil, as it adds very materially to the life of the coil. It also has the added feature of the entire coil acting as a heat absorbing element, no portion of which is outside the heating zone.

The coil as constructed consists of a plurality of tubes arranged in layers, each tube in one layer being connected to a tube in another layer by means of steel blocks bored through in line with the tubes, one side being counterbored and threaded to receive the threaded end of the tube and the other end of the bored hole is threaded to receive removable threaded plugs which act as closures when the coil is in operation, or when removed will afford means for inspecting and cleaning the tubes. Lengthwise with the blocks is a bore hole, preferably the size of the inside diameter of the tubes, and in communicating with the two previously described bore holes, the axis of the longitudinal bore holes intersects the axes of the two transverse bore holes; the upper end of the longitudinal bore hole is threaded to receive a threaded plug which has the same function as the two previously described plugs.

20 The longitudinal bore hole is not bored beyond the point where it makes full communication with the second tube opening, although it could be drilled through and threaded the same as the other end, but nothing would be gained by this 25 and expense would be incurred.

In place of threading or screwing the tubes into the blocks, they may be welded in, the blocks then being only counterbored to receive the tubes and not threaded.

30 To hold the coils as a unit, I employ a three piece cast iron or steel clamp, usually three in number to each coil, one near each end and one in the middle; the middle portion of the clamp is grooved out with semi-circular grooves to receive the tubing and so spaced as to give the proper spacing of the tubes; the upper and lower portions of the clamp are also grooved out in a similar manner to the middle portion and have extended ends through which pass bolts to fasten 40 the top, bottom and middle sections together, thus securely fastening the various tubes into a single rigid unit.

I prefer to construct the coil in a symmetrical manner as to spacing of the tubes, that is to say 45 any lower tube is equidistant from the two tubes immediately above it, and vice versa, any upper tube is equidistant from the two tubes immediately below it.

Furthermore, the blocks at one end of the coil 50 are inclined uniformly in one direction or the other and at the opposite end of the coil in the reverse direction. By this expedient, tubes placed parallel with the longitudinal axis of the coil will connect opposite blocks, and when all the blocks 55 are so connected, the structure so assembled will form a continuous coil of a single passage with two open ends, one for inlet and the other for outlet connection. This is all clearly shown in the drawing—Figures 2, 3 and 4.

60 The blocks may be placed vertically instead of inclined, but if this is done, the tubes will not be parallel with the axis of the coil and it might be difficult to insert a cleaning tool into the tube, as it would be sprung out of line a distance equal 65 to the spacing between tube centers. For this reason, I prefer the first described method of construction, but I do not wish to be limited to that type, as the last mentioned construction will be operative.

70 What I claim as new is:

1. In an apparatus for cracking petroleum oils for the production of lower boiling hydrocarbon oils, a metallic cracking coil substantially resist-

ant to the action of sulphur, said metallic coil being composed of an iron and chromium alloy, said chromium in the alloy being in such proportions as to substantially prevent the corrosive action of sulphur.

2. In an apparatus for cracking petroleum oils for the production of lower boiling hydrocarbon oils, a metallic cracking coil substantially resistant to the action of sulphur, said metallic coil being composed of an iron chromium nickel alloy, 10 said alloy being in such constituent proportions as to substantially prevent the corrosive action of sulphur.

3. An apparatus for cracking hydrocarbons comprising a furnace, a cracking coil positioned 15 within said furnace, said coil being formed of material comprising an alloy of iron and chromium substantially resistant to the corrosive action of sulphur and means in said furnace for supplying products of combustion thereto.

4. An apparatus for cracking hydrocarbons comprising a furnace, a plurality of tubes in said furnace through which the oil to be cracked is passed under pressure, said tubes being formed of an alloy of iron chromium and nickel, substantially resistant to the action of sulphur under the conditions of cracking, and means for passing hot products of combustion over said tubes to crack the oil therein.

5. In the art of converting higher boiling hydrocarbon oil into lower boiling hydrocarbon oil, the improvement which comprises heating said oil to a cracking temperature in a metallic coil composed of an alloy of chromium and iron, said coil being substantially resistant to the action of sulphur.

6. In the art of converting higher boiling hydrocarbon oil into lower boiling hydrocarbon oil, the improvement which comprises heating said oil to a cracking temperature in a metallic coil composed of an alloy of chromium, nickel and iron, said coil being substantially resistant to the action of sulphur.

7. An apparatus for use in a process wherein hydrocarbon oil is subjected to cracking conditions which comprises a container adapted to receive hydrocarbon oil undergoing cracking composed of an alloy of iron and chromium substantially resistant to the corrosive action of sulfur or sulfur compounds.

8. An apparatus for use in a process wherein hydrocarbon oil is subjected to cracking conditions which comprises a container adapted to receive hydrocarbon oil undergoing cracking composed of an alloy of iron, chromium and nickel substantially resistant to the corrosive action of sulfur or sulfur compounds.

9. A process of treating hydrocarbon oil which comprises subjecting hydrocarbon oil to a temperature sufficiently high to effect cracking thereof while in contact with a container composed of an alloy of chromium and iron substantially resistant to the corrosive action of sulfur or sulfur compounds.

10. A process of treating hydrocarbon oil which comprises subjecting hydrocarbon oil to a temperature sufficiently high to effect cracking thereof while in contact with a container composed of an alloy of chromium, nickel and iron substantially resistant to the corrosive action of sulfur or sulfur compounds.

JOHN C. BLACK.
